Primary Examiner — Bao-Yen T Nguyen*(74) Attorney, Agent, or Firm* — MASCHOFF BRENNAN(57) **CLAIM**

The ornamental design for a display screen with graphical icon, as shown and described.

DESCRIPTION

FIG. 1 is a front view of a computing device display screen with graphical icon showing our new design;

FIG. 2 is a front view of a second embodiment of a display screen with graphical icon showing our new design;

FIG. 3 is a front view of a third embodiment of a display screen with graphical icon showing our new design;

FIG. 4 is a front view of a fourth embodiment of a display screen, or portion thereof, with graphical icon showing our new design; and,

FIG. 5 is a front view of a fifth embodiment of a display screen, or portion thereof, with graphical icon showing our new design.

The broken lines illustrate a display screen and form no part of the claimed design. The broken lines in FIGS. 3, 4, and 5 illustrate portions of the icon and form no part of the claimed design.

1 Claim, 5 Drawing Sheets(56)
